INVENTOR
WILLIAM H. HALL.

BY *Geckenslaugh Co.,* ATTYS.

UNITED STATES PATENT OFFICE.

WILLIAM HERBERT HALL, OF OSHAWA, ONTARIO, CANADA, ASSIGNOR TO THE PEDLAR PEOPLE LIMITED, OF OSHAWA, CANADA, A CORPORATION.

CORRUGATED PIPE OR CULVERT.

Application filed April 11, 1924. Serial No. 705,896.

This invention relates to improvements in corrugated pipes or culverts, and the objects of the invention are to facilitate the removal of ice and snow from the interior 5 of such pipes when used as culverts, and to prevent the formation of ice in the corrugation on the inside of the culvert.

And it consists essentially of a corrugated pipe or culvert having a smooth metallic 10 lining preferably of lighter material and connected thereto, as shown and described in the accompanying specification and drawings.

In the drawings:
15 Figure 1 is a longitudinal sectional elevation of an embodiment of the invention.

Figure 2 is a longitudinal sectional elevation taken at right angles to Figure 1.

Figure 3 is an end view partially in section.

In the drawings, like characters of reference indicate corresponding parts in all the figures.

Referring to the drawings:

25 A indicates the corrugated pipe or culvert proper constructed of suitable sheet metal in the usual form, having overlapping edges fastened by rivets 10. B indicates a smooth lining for the culvert or pipe, preferably 30 made of lighter material than the body of the pipe and also formed with overlapping edges. The overlapping edges of the lining and of the culvert itself are preferably secured by the same rivets, as indicated in 35 Figure 3, these rivets extending through the lapped joint of both the culvert A and the lining B.

The lining B at the start or finish of any 40 length of pipe or culvert is turned over the edge of the culvert A to prevent the entrance of water or snow between the pipe A and the lining B. As shown, a flange 11 is formed on the lining B which is turned over the edge of the culvert or pipe A, as shown 45 in Figure 1, and it will be understood that a similar flange will be formed at the beginning or end of any length of pipe.

The lining B projects a distance beyond the pipe or corrugated section A to provide a lappage 12 which will project into the 50 next adjacent section. The corrugated pipe or culvert A, such as described, is used very largely as a culvert beneath roads, and in the spring of the year the ditches on the sides of the road are liable to be full of 55 water which, with the ordinary form of culvert, freezes solidly in the corrugations and cannot be removed therefrom.

With the smooth lining described, however, at the first melting in the spring, the 60 ice may be readily pushed out, thereby enabling the culvert to be readily cleared. It will be seen that very little additional expense is involved in placing the smooth lining in place, since it may be made of lighter 65 material and may be held in position by the same rivets.

As many changes could be made in the above construction and many widely different embodiments of my invention within 70 the scope of the claim, constructed without departing from the spirit or scope thereof, it is intended that all matter contained in the accompanying specification and drawings shall be interpreted as illustrative and 75 not in a limiting sense.

What I claim as my invention is:

A corrugated culvert section formed from a single sheet of metal and having the edges overlapped, a lining for the culvert formed 80 with overlapping edges and securing means through the overlapped edges of the lining and the metal to form an overlapped joint, the lining being folded over the culvert at one end to prevent leakage and formed with 85 a projection at the other end protruding beyond the culvert to provide a lappage for an adjacent section.

In witness whereof I have hereunto set my hand.

WILLIAM HERBERT HALL.
